TOWEL RACK OR SIMILAR ARTICLE

Carl C. Hillgren, 2801 Bay Shore Drive,
Newport Beach, Calif.

Filed Jan. 30, 1956, Ser. No. 39,962

Term of patent 14 years

(Cl. D4—3)

Pig. 1.

Pig. 2.

Pig. 3.

Pig. 4.

The broken away portions in the drawing figures shown in broken lines indicate indefinite length.

I claim:

The ornamental design for a towel rack or similar article, substantially as shown and described.
